TABLE

Otto M. Blizzard, Dayton, Ohio

Application September 8, 1931. Serial No. 561,567

8 Claims. (Cl. 45—31)

My invention relates to tables.

It is the object of my invention to provide a table which may be assembled or disassembled readily for use in hotels, schools and churches as a display or banquet table.

It is particularly my object to provide a table in which the structure in one table can interlock with and act as a supporting member for an adjacent section of a table which has been erected to extend the first table.

It is my object to provide means to interlock each section of the table and to lock the interlocking means in a common vertical standard between the tables.

It is a further object to provide means of detachably locking the table tops in abutment one with the other.

It is my object to provide a table which may be assembled as a single table or may be indefinitely extended in a series of sections all of the same character.

It is a further object of my invention to provide means of supporting the table on wedge shaped hooks on the longitudinal brace which connects the vertical members of the table together to form the support for the table top and to form with such wedge-shaped hooks an attaching means by which the hooks can be directly introduced into the vertical member at right angles thereto, thereby making it possible to extend the table in a series of table sections.

Referring to the drawings:

Figure 1 is a top plan view of the table assembled with an adjacent table indicating in dotted lines the arrangement of the supports for the table and with one of the table sections broken away to show the means of interlocking the table top to the vertical table support;

Figure 2 is a section on the line 2—2 thereof; Figure 3 is a section on the line 3—3 of Figure 1;

Figure 4 is a detail view partially in section showing the method of locking and interlocking the horizontal table members with the vertical members;

Figure 5 is a section on the line 5—5 of Figure 4;

Figure 6 is a section on the line 6—6 of Figure 4;

Figure 7 is a section enlarged to show the detail of connection of the table top to the vertical table top supporting member.

Referring to the drawings in detail, 1 and 2 indicate a pair of upright members having a space 3 therebetween, which members are mounted upon a foot member 4. On the top of

these members is mounted a table support cap member 5 having upwardly extending, laterally disposed ends 6 on which the table rests directly. The table top 7 is provided with depending shoulders 8 engaging on the outer ends of the cap member 5.

The bottom of this table member is spaced from the top 9 of the cap member, there being a space 10 therebetween.

The under side of the table top 7 carries a transverse shoulder member 11 on the under side thereof which engages with the outside face of the cap member 5. Pivoted on the under side of the table top on the stud 12 is a swinging locking lever 13 having a locking nose 14 which enters the slot 15 beneath the cover plate 16 in the cap member. Thus, the table top is detachably locked to the vertical table supports and is insured against motion in any direction by the members 8 and 11.

The vertical members 1 and 2 are joined together by a pair of vertically spaced studs 17 and 18 on which are mounted the hooks 19 having the wedge-shaped faces 20, which hooks are extensions of the plates 21 which are attached by the attaching means 22 to the horizontal connectors between the vertical upright members 1 and 2 at either end of the table. This horizontal connector is designated 23.

It will be noted that each plate 21 carries a pair of hooks that are provided with the wedge-shaped slots having the faces 20 forming the hook members 19. As these hooks are spaced apart there can be no vertical movement of the member 23 but it may be directly connected to the members 1 and 2 by the insertion of the thin metal plate in the slot 3 which can be lowered so that its hook members 19 can engage the transverse members 17 and 18. When this takes place the spring-pressed locking plungers 24 can be released so that the head 25 thereof enters the enlarged space 26 formed in the adjacent walls of the vertical members 1 and 2 at the slot 3, thereby locking the horizontal connecting member 23 to the vertical members 1 and 2.

In the upper edge and adjacent each end of the members 23 is a notch 23a, which has extending therefrom, through the member to the ends thereof, a hole 23b. In the part of this hole remote from the notch is placed a thimble 23c. Extending through each thimble of each hole is the plunger 24, which has on one end the head 25. Between this head and the bottom of the thimble through which the reduced part of the plunger passes, is a spring 24a which tends to hold the plunger in an outwardly extended

position. The plunger has on its end, remote from the head, a shoulder 24b, which abuts the end of the thimble to limit the outward movement of the plunger.

5 It will be noted that the space 3 between the vertical members 1 and 2 is wide enough to accommodate a pair of the plates 21 and their hooks. Thus, the vertical members 1 and 2 can be used not only to support the immediate table 10 top over them resting upon them but can be used to connect adjacent vertical members supporting an adjacent table top so that the table tops will be an abutment and form a continuous table structure.

15 The interconnecting horizontal member used for this purpose and designated here as 24 may be either as long as the member 23, longer or shorter depending upon the amount of overhang of the table top ends over the vertical supports. 20 This is a matter of choice, but, when the adjacent tables are thus interlocked, they form one long continuous structure that is rigid against movement in any direction.

It will be understood that I desire to comprehend within my invention such modifications as 25 may be necessary to adapt it to varying conditions and uses.

Having thus fully described my invention, what I claim as new and desire to secure by Letters 30 Patent, is:—

35 1. In combination, a table having upright and horizontal members, means having hooks thereon for interconnecting said members, and a second horizontal member comprising a connector to an adjacent table, and hook means thereon adapted to engage with and overlap one of the hooks of the first mentioned horizontal member and engaging with one of the vertical supports of the table.

40 2. In combination in a table structure of a pair of spaced vertical supporting members, and a pair of horizontally-disposed connecting members, hook means thereon adapted to be inserted between said vertical members in overlapping engagement with one another, and common hook supporting means interconnecting said vertical members.

45 3. In combination in a table structure of a pair of spaced vertical supporting members, a pair of horizontally-disposed connecting members, hook means thereon adapted to be inserted between said vertical members in overlapping engagement with one another, common hook supporting means interconnecting said vertical members, and spring-pressed locking members arranged 50 over said hook members carried by the respective

horizontal members and entering enlarged spaces between the vertical members.

4. In combination, spaced vertical supporting members comprising spaced uprights connected by spaced studs, a foot member and a cap member, a table top mounted on said cap member, a locking lever on the table top to detachably lock said table top to said cap member, a horizontally-disposed connector member having hooks on the end thereof insertible between the upright members of each support to engage the studs, said hook members being formed with wedges on the end thereof. 80

5. In combination, spaced vertical supporting members comprising spaced uprights connected by spaced studs, a foot member and a cap member, a table top mounted on said cap member, a locking lever on the table top to engage the cap member and detachably lock said table top to said cap member, a horizontally-disposed connector member having hooks on the end thereof insertible between the upright members of each support to engage the studs, said hook members being formed with wedges on the end thereof, 85 and means to detachably lock said horizontal connector member. 90

6. In a table top, a vertical support having a cap member having a slot therein, a lever pivoted adjacent the longitudinal center of the table on the under side of said table top having one 105 end thereof adapted to engage in the slot in the top of said cap member.

7. In a table top, a vertical support having a cap member, a lever pivoted on the under side of said table top having one end thereof adapted 110 to engage in a slot in the top of said cap member substantially at its center, and means depending from the bottom of said table top adapted to engage the ends of the cap to prevent its movement laterally and longitudinally. 115

8. In combination, of a plurality of pairs of spaced, vertically-disposed table supports, a foot member on the bottom of each pair, a top member on the top of each pair, a pair of spaced interconnecting rods extending from one vertical 120 member to the other of each pair, horizontal interconnecting members, each having a plate on each end thereof projecting therebeyond, said plates being provided with hook members formed by diagonal slots in which said rods are received, 125 said parts being so arranged that two horizontal connecting members with their hooked plates introduced side by side between the supports on the rods may be supported at right angles to the vertical members. 130
